UNITED STATES PATENT OFFICE

ADOLPHE C. PETERSON, OF MINNEAPOLIS, MINNESOTA

SUPERCHARGING MULTIPOWER SYSTEM

Application filed June 7, 1929. Serial No. 369,253.

My invention relates to power systems for aeroplanes and has certain particular features wherefore it is called a supercharging multi-power system.

The principal objects of my invention are to provide a power system for aeroplanes which shall be simple in construction, reliable in use and which shall be light in weight while having ruggedness and durability. A principal object is to provide a power system for such use which shall by reason of its simplicity be more free from fault and failure, and which by reason of its method of construction and adaptation to the aeroplane shall be relatively more light in weight and stronger in construction. An object is to provide a power system which shall have especial characteristics regarding the charging with air and fuel. In general the object is to provide an improved and simplified power system for aeroplane use.

In the accompanying drawings which illustrate my invention like characters refer to like parts throughout the several views. The principal devices and combinations of devices comprising my invention are as hereinafter described and as defined in the claims.

Figure 1 is a view chiefly in plan, some of the parts being in horizontal section on the line I—I of Figure 2 and some of the parts notably the wing covering being removed for the sake of clearness in the illustration of the particular features.

Figure 2 is a view in vertical section on the line II—II of Figure 1 showing especially the cross section of the wing and the engine mounting.

Figure 3 is a view in cross section transverse to that of Figure 2, this section being a vertical section on the line III—III of Figures 1 and 2, it being noted that a similar section through any of the engines is the same.

Figure 4 shows a modified mounting.

Referring again to the drawings, the numeral 1 indicates a fuselage or a sea-plane hull to which my device is applied, this hull or fuselage being shown relatively slender in its width in order to better illustrate the remaining parts. The hull 1 (so-called hereinafter for brevity) has a monoplane wing

attached to it and this wing has a rear spar 2 placed transversely of the hull 1 and the wing has a front or forward spar or beam 3 which is of a truss form or box girder form and has in that portion of its length near the hull 1 a cross section substantially square and having at the four corners of the square the four members 4 each of which may be of angle steel or duralumin or of T section or other section individually. The box section type spar or beam 3 forms a mounting for the engines and also forms the spar of the monoplane wing and there are mounted in this box section beam 3 four engine crank cases, each denoted 5. The crank cases are constructed preferably of duralumin or other light metal and they have such form that they are readily mounted within the four members of the box type spar and so that they contribute also to the strength of the box section spar 3.

Each engine crank case 5 has a crank shaft 6 individually related to it and each crank shaft 7 has an individually related ratchet 8 through which the individual crank shaft is adapted to impart driving torque to its related individual mitre gear 9 and through the latter to one of two mitre gears 10 and 11, respectively, one of the latter driving a propeller shaft 12 and the other driving a propeller shaft 13. The propeller shafts 12, 13 drive propellers 14, 15, respectively. The ratchets 8 are each of such construction that they will procure engagement of the related engine with the propeller shaft related only in driving torque of the related engine exerted in the direction driving the related propeller forwardly. There are four engines each pair of two driving one propeller 14 or 15 and thus each pair of engines must have one having crank shaft rotation one way and one having crank shaft rotation the other way.

Each engine crank case 5 has secured to it on its forward side, that is the side directed to the leading edge of the wing, cylinders 16, there being two or more of such cylinders in each engine. Only two are shown in each for simplicity in illustration. The cylinders 16 lie with their longitudinal axes substan-

tially horizontal and in a single horizontal plane. Each cylinder 16 has an injection nozzle 17, diagrammatically shown and a related fuel conduit 18 to feed the nozzle 17, and the related engine has a fuel pump and distributor unit 19 secured on the engine and adapted to be driven by the engine crank shaft. The connections or driving of the fuel distributor and pump by the engine crank shaft is not specifically shown since this is not involved in the invention and may be of any type.

Each cylinder 16 has related to it and enclosing it a cylindrical air conduit chamber 20 which lies also horizontally and is directed forwardly from the crank case 5. Within each air conduit chamber 20 and disposed between its inner wall and the exterior wall of the related cylinder 16 there are cooling fins 21 fixed to the cylinder wall whereby air passing through the air conduit chamber 20 will cool the cylinders 16. The fins occupy a portion of the length of the air conduit chamber 20 as shown.

Each air conduit chamber 20 at its forward end has formed with it or attached to it an air gathering funnel or nozzle 22 directed to the leading edge of the wing. Thus each air conduit chamber and its funnel or nozzle 22 constitute an air gathering and directing means directed to the leading edge of the wing and this gathering means is normally open to the atmosphere as shown so that air may flow backwardly through the air conduit chamber in flight of the aeroplane. Each air conduit chamber 20 near its rear end is free from the fins and constitutes a small collecting chamber adjacent to a pair of air inlet ports 23 located on the sides of the cylinder 16 substantially at a height such that the pair of air inlet ports 23 will be uncovered by the piston of the cylinder when at its outermost position and when passing through the induction and expulsion or exhaust portion of the cycle.

Each cylinder 16 has also substantially on the same cross-sectional plane as that occupied by the air inlet ports a pair of exhaust ports 24 one on the lower and one on the upper side of the cylinder 16. The air inlet ports 23 are open to the air conduit chamber but the exhaust ports are not but are open to the atmosphere as shown the exhaust ports delivering by short individual conduits 25 through the wing covering.

The funnels or nozzles 22 at their extreme forward end, that is at their open mouths may be closed by shutter valves 26 which are manually controlled and slide along the inside or outside of the leading edge of the wing so as to close the funnels. There is preferably one shutter 26 for each engine adapted to close the funnels of that engine.

The funnels 22 may each receive air under low pressure say five or ten pounds from

conduits 27 passing along the side of the funnels from a Root's blower or other type air blower or compressor 28 located in the hull 1 and driven by an independent engine 29. The engine 29 may be only a small engine adapted to drive the blower for a short time on starting and landing or it may be an engine having connection with an independent propeller. It is contemplated that blower 28 will draw air from atmosphere and compress to five or ten pounds, and that when not operating air cannot pass through the blower from the funnels, by reason of the construction of the blower but light flap valves may be interposed in the conduits 27 to prevent return flow.

In the use of my device it is contemplated that each fuel pump and distributor unit receives liquid fuel from any containers in the aeroplane and that the engines will preferably operate on the Diesel principle, but not necessarily so, and that each engine will have its separate starting means or that means will be provided whereby each engine may be separately started. In starting the auxiliary engine 29 is first started and drives blower 28 and the shutters 26 are closed so that the funnels and air conduit chambers are closed at the front end to the atmosphere so that the blower 28 may then fill the funnels and conduits with air under five or ten pounds pressure. The engines are then started and the fuel distributors distribute fuel to each cylinder, each engine having its own timing, and thus the engines receive air from the compressor 28 and each operates as a two cycle engine and the plane may then be released and go on its way. When in the air and having a substantial speed, or when given a diving or descending angle the plane will gather high speed, and thereupon the shutters 26 may be opened to open funnels 22 to atmosphere at their ends or mouths. These mouths as shown are in the leading edges of the wing, and the plane having high speed air will be gathered in the funnels and forced under pressure backwardly through the air conduit chambers and thence at each opening of air inlet ports in a cylinder will pass into the cylinder and be directed by the conformation of the related piston head to the head of the cylinder and will assist in blowing the exhaust out of the exhaust ports to atmosphere from the lower and upper side of the wing, the air will continue to flow during the entire period at which the air inlet ports are open in a cylinder and thus there will be some supercharging of the cylinder with air. The air inlet ports may be made of such length that they remain open slightly longer than the exhaust ports for this purpose. (Or positively acting port controlling means actuated by the crank shaft may be provided to better control the charging.)

Thus each cylinder is exhausted and charged

with fresh air under low pressure which is compressed and subsequently combustion follows. Each funnel or nozzle may have such shape as to contribute to the creating of air pressure. It is contemplated that in high speed aeroplanes this air pressure created by the nozzles will be amply sufficient to create the charging air pressure. Any means may be provided for charging on starting, other than that shown. It is contemplated that part of the air from the nozzles may cool and only a part flow into the air inlet ports but preferably the more simple construction is used.

Figure 4 shows a modified form of mounting of the engines, the structure of spar A in this form constitutes also a crank case for the individual engines the spar being formed of metal welded or united in the shape shown, in two sections, longitudinally if preferred, and the spar material has apertures B in the sides for access to the crank shaft and has apertures C on the front side for the cylinders 16. Thus the spar in this form performs the dual function of supporting the wing and also forming a crank case at the part of its length where the engine lies.

While I have shown particular devices and combinations of devices in the illustration of my device I contemplate that other detailed devices and combinations of devices may be used in the realization of my device without departing from the spirit and contemplation thereof.

What I claim is:

1. In an airplane engine system, wings, supporting spars in the wing, an engine crank case supported longitudinally in the spars, cylinders attached to the crank case and directed forwardly from the spar, fins on the cylinders, in connection with surfaces of the wing disposed to direct cooling air along the fins.

2. In an airplane engine system, wings, supporting spars in the wings, an engine crank case supported longitudinally in the spars, cylinders attached to the crank case and directed forwardly from the spar in the leading edge of the wing, cooling fins on the cylinders, and means whereby the engine propels the airplane propeller.

3. In an airplane system, wings, supporting spars in the wing, a plurality of engine crank cases supported longitudinally in the spars, each crank case having cylinders attached and directed forwardly from the spars in the leading edge of the wing, cooling fins on the cylinders, and means whereby the engine propels the airplane propeller.

4. In an airplane engine system, wings, supporting spars in the wing, a plurality of engine crank cases supported longitudinally in the spars, each crank case having cylinders attached and directed forwardly from the spars in the leading edge of the wing, cooling fins on the cylinders, and chambers

disposed in the leading edge of the wing for direction of air from the leading edge of the wing to the individual cylinders.

5. In an airplane engine system, wings, supporting spars in the wing, a plurality of engine crank cases supported longitudinally in the spars, each crank case having cylinders attached and directed forwardly from the spars in the leading edge of the wing, cooling fins on the cylinders, and chambers disposed in the leading edge of the wing for direction of air from the leading edge of the wing by fins of the cylinders, thence to air pockets, thence as controlled by the engine pistons through ports into the cylinder exhaust occurring through exhaust ports of the cylinders to the atmosphere.

6. In an airplane engine system, wings, supporting spars in the wing, a plurality of engines mounted with their crank shafts longitudinally in the spars, cylinders directed forwardly from the spars in the leading edge of the wing, cooling fins on the cylinders, and means whereby the crank shafts drive a propeller means.

7. In an airplane engine system, a wing supporting means, an engine having individual engine cylinders directed forwardly in the direction of the flight of the airplane, air gathering means directing air encountered in the forward flight to each engine cylinder for the cooling thereof.

8. In an airplane engine system, a wing supporting means, an engine having individual engine cylinders directed forwardly in the direction of the flight of the airplane, air gathering means directing air encountered in the forward flight to each engine cylinder for the cooling thereof and thence to air chambers through inlet ports in the engine cylinders as governed by the engine pistons and thence through the exhaust ports of the engine cylinders.

9. In an airplane engine system, wing supporting means, an engine having individual engine cylinders directed forwardly in the direction of the flight of the airplane, air gathering means directing air encountered in the forward flight to each engine cylinder for the cooling thereof, and thence to air chambers and through inlet ports to the engine cylinders and thence through the engine exhaust ports.

10. An airplane engine system, wing supporting means, an engine having individual cylinders directed forwardly in the direction of the flight of the airplane, air gathering means directing air encountered in the forward flight of the airplane to each engine cylinder for the cooling thereof, and thence to air chambers and through inlet ports to the engine cylinders, means whereby the air gathering means may be closed to the air and whereby supplementary air charging

means may be operated to blow air to the inlet ports.

11. An engine in an airplane having related an air gathering funnel means for normally 5 charging the engine with air for combustion and a supplementary air charging means power driven by auxiliary power means for charging in conditions wherein normal charging does not suffice.

12. A wing spar comprising a box girder horizontally substantially placed in the wing as its supporting spar, a section of the box girder having a size sufficient for and placement for the revolution of an engine crank 15 shaft, cylinders related and attached to the spar, pistons cooperating with the crank shaft to drive the propeller shaft of the airplane.

13. The novel means in claim 12 and air 20 gathering means for each cylinder receiving air from the leading edge of the wing for cooling.

14. The novel means in claim 12 and air gathering means for each cylinder receiving 25 air from the leading edge of the wing for cooling and means directing the air after cooling to the engine cylinder for charging.

15. An airplane having an air gathering means receiving air encountered in flight, in 30 combination with a plurality of engines each adapted to be normally charged in its combustion chambers for combustion of fuel by air from the air gathering means, means related to each engine for delivery of fuel for combustion in its combustion chambers, and a supplementary air charging means power driven by auxiliary power means, for air charging in conditions wherein normal charging does not suffice.

16. In an airplane, an engine having cylinders and cooperating pistons driving a propeller, an air gathering means having forwardly directed mouth means receiving air in flight, inlet and exhaust ports for each 45 cylinder whereby the cylinder may be charged periodically by air from the air gathering means for combustion in the two cycle manner, and means for the introduction of fuel periodically to each cylinder.

17. In an airplane, an engine having cylinders and cooperating pistons driving a propeller, an air gathering means having forwardly directed mouth means receiving air in flight, inlet and exhaust ports for each cylinder whereby the cylinder may be charged periodically by air from the air gathering means for a combustion in the two cycle manner, means for the introduction of fuel periodically to each cylinder, and a supplementary 55 air charging means power driven by auxiliary power means for air charging in conditions wherein normal charging does not suffice.

18. In an airplane, an engine having cylinders and cooperating pistons driving a

propeller, an air gathering means having forwardly directed mouth means receiving air in flight, each cylinder having a related inlet port governed to admit air to its cylinder during a charging period, each cylinder 70 having a related exhaust port governed to exhaust products of combustion during the charging period, and means for the introduction of fuel periodically to each cylinder.

19. In an airplane, an engine having cylinders and cooperating pistons driving a propeller, an air gathering means having forwardly directed mouth means receiving air in flight, each cylinder having a related inlet port governed to admit air to its cylinder 75 during a charging period, each cylinder having a related exhaust port governed to exhaust products of combustion during the charging period, means for the introduction of fuel periodically to each cylinder, and a supplementary air charging means power driven by auxiliary power means for air charging in conditions wherein normal charging is not operative.

20. In an airplane, a plurality of engines 90 each having cylinders and cooperating pistons driving a propeller, an air gathering means having forwardly directed mouth means receiving air in flight, each cylinder having a related inlet port governed to admit air to its cylinder 95 during a charging period, each cylinder having a related exhaust port governed to exhaust products of combustion during the charging period, means for the introduction of fuel periodically to each cylinder, and a supplementary air charging means power driven by auxiliary power means for air charging in conditions wherein normal charging is not operative.

In witness whereof I have hereunto set 105 my hand this 3d day of December, 1928.

ADOLPHE PETERSON.
